Primary Examiner — Barbara Fox*Assistant Examiner* — Dana K Weiland*(74) Attorney, Agent, or Firm* — Andrew Wilford(57) **CLAIM**

The ornamental design for a portion of a monitor with an icon, as shown and described.

DESCRIPTION

The sole FIGURE is a front view of a portion of a monitor with an icon, showing our new design.

In the drawing, the dashed-line box surrounding the icon represents a portion of a monitor screen and forms no part of the claimed design.
